LOOM SHUTTLE ADAPTED FOR AUTOMATICALLY STOPPING THE LOOM ON SUBSTANTIAL DEPLETION OF THE WEFT

Robert Heinrich Stehli, Zurich, Switzerland

Application May 15, 1933, Serial No. 671,224
In Switzerland May 19, 1932

3 Claims. (Cl. 139—205)

This invention relates to loom shuttles adapted for automatically stopping the loom on substantial depletion of the weft, by breaking the weft thread, and comprising a weft thread feeler member which is arranged on the spool supporting spindle of the shuttle and which cooperates with the weft thread wound on the spool from within a tubular carrier for the thread through a slot in said carrier, the shuttle being applicable to looms 10 that are provided with a weft thread detector arranged centrally between the sides of the loom and adapted for immediately stopping the loom before the next following throw of the reed.

Loom shuttles comprising weft thread feeler 15 members of this kind, are known, wherein the feeler member is rocked on depletion of the weft thread by action of its own weight or of a spring, in order to cooperate with a special stopping device associated with the loom.

According to the present invention the weft 20 feeler mechanism is adapted to be rocked through the slot shortly before the depletion of the weft, by effect of at least one of the impacts imparted to the shuttle incidental to the shuttle buffering 25 the shuttle box or the picking of the shuttle, in such manner, that further unwinding of the thread is resisted, so that immediately on the shuttle leaving the shuttle box, during its next traverse, the thread is broken and thus the central weft thread detector is rendered operative.

On operation of the central weft thread detector, the loom is stopped before the slay has completed its next throw, due to the thread end still connected to the fabric being shorter than 35 half the width of the fabric. Since experience has shown that in breaking the weft thread in this manner ordinarily the point at which the thread is severed lies exteriorly of the shuttle, it is not necessary to thread through the thread end of 40 the fresh supply spool, as the fresh thread end can simply be twisted together with the old thread end and then be pulled through by means of the latter end. As with the device according to the invention the loom is stopped by means of the 45 central weft thread detector, no other stopping means are necessary.

The operation of such a device has now shown that under certain circumstances overstretched picks are apt to occur, in the first place, for the 50 reason that the device operates on arrival of the shuttle in the shuttle box, due to the shuttle being retarded or blocked (by the shuttle binder), whereby the weft thread is strained or overstretched. Moreover, overstretched picks are 55 apt to arise, when multiple box looms are in-

volved, the slay, in such looms being moved to and fro and the shuttle box up and down, so that the weft thread, if blocked when the shuttle arrives, is strained during the traverses of the second shuttle in opposite directions. 60

In order to improve the operation of the device, it is advantageous to provide means for ensuring that the device is rendered operative not when the shuttle arrives in the shuttle box, but rather only after its departure therefrom. Means 65 for this purpose may include a spring which cooperates with the weft thread feeler member in the sense of opposing the rocking movement thereof, thus preventing it from being rocked on the arrival of the shuttle, but only on the departure thereof. The impact imparted to the shuttle is cushioned by the retarding action exercised on the shuttle at the end of its traverse, the kinetic energy of the shuttle then being less than at the beginning of the traverse. In actual 70 practice the effect of such a spring is, however, not altogether reliable. This is due to the fact that though the residual kinetic energy of the shuttle is less at the end than at the start of its traverse, the difference is not sufficiently great 75 for ensuring a safe operation of the spring brake at all times.

In a particularly advantageous constructional form of the invention the operation referred to immediately above is obtained by including a loose 80 stop member in the spool supporting spindle so as to be adapted to adjust itself into different positions by effect of the impacts imparted to the shuttle during the throws of the slay forward and rearward, thus blocking the weft feeler member 85 on the arrival of the shuttle in the shuttle box and releasing said member on the shuttle starting to move out of the shuttle box, so that the weft feeler member can only be moved into operative position by effect of the impact imparted 90 to the shuttle for starting the same moving.

In the accompanying drawing several constructional forms of the invention are illustrated by way of example only, in which

Fig. 1 shows a sectional side elevation of a 100 first constructional form of the invention;

Fig. 2 shows a plan view of Fig. 1;

Fig. 3 shows a part-section of a spool supporting spindle;

Fig. 4 represents a section similar to Fig. 3 of 105 a second constructional form of the invention;

Fig. 5 shows a cross-section on the line V—V in Fig. 4;

Fig. 6 shows a side elevation of a spindle inclusive of a quill for the weft windings, partly 110

in section, for a third constructional form of the invention;

Fig. 7 illustrates a plan view of Fig. 6, also partly in section, and

5 Fig. 8 is a cross section on the line VIII—VIII in Fig. 6.

Referring to the constructional form of the invention as shown in the Figures 1 to 3 of the drawing, 1 represents the loom shuttle in which 10 the spool supporting spindle 2 is pivotally arranged, in a manner known per se. In a recess 3 of the spindle 2, a weft feeler arm 5 is pivotally mounted by means of a pivot pin 4. A tubular weft carrier or quill 6 is provided with a slot 7 15 at a portion thereof which overlies the arm 5, for permitting this arm to swing through this slot. At that end of the weft carrier at which the feeler arm 5 is situated, exteriorly of the weft windings proper, a spare winding 8 including a 20 length of weft thread of a few meters is placed.

The operation of the device is as follows:

Due to its particular construction, the weft feeler arm has the tendency to swing outwardly through the slot 7 in response to the impacts 25 exerted on the shuttle on its arrival in the shuttle box and at the start of its movement respectively. However, as long as there is still an amount of weft material present on the quill sufficient to hold the feeler arm back, the latter 30 rests against the inner windings of the weft. When, on the other hand, the weft is unwound so far that only the spare winding 8 is left, during the next following impacts, the feeler arm 35 5 is swung into the position indicated by chain dotted lines in Fig. 3. The thus outwardly rocked feeler arm prevents further unwinding of the weft thread, so that incidental to the next traverse of the shuttle the thread is broken and 40 thus the central weft thread detector rendered operative.

In the Figs. 4 and 5 a constructional form of the invention is shown in which the feeler arm 5a is swingably arranged on the pivot pin 4 is so constructed that it is adapted to be rocked in the direction opposite to that described in connection with the previous constructional form.

In the constructional form as per the Figs. 6 to 8, a weft feeler arm 14 is swingably mounted in a slot 2a of the spool supporting spindle 2 by means of a pivot 15 and provided on an extension 16 with a feeler portion 17 which cooperates with the weft windings by passing through a slot 7 formed in the quill 6. In a lateral bore 18 of the spindle 2 a ball 19 is guided so as to be adapted to roll to and fro in said bore from one end position to the other in accordance with the directions of movement of the slay. During the end movement of the shuttle on its traverse the slay moves forwardly and the ball 19 assumes its inner end position i. e. enters on the path of the weft feeler arm 14, thus preventing the same from being rocked outwardly. Thereupon the slay moves backwardly while the stop ball occupies its outer end position in which it is moved out of the path of the feeler arm 14, so that during the starting movement of the shuttle on its traverse the feeler portion 17 is adapted to contact with the weft windings. Therefore, the arm 14 can only be outwardly rocked by effect of the impact imparted to the shuttle at the start of its traverse, when the weft is so far unwound that only the spare winding 8 is left. On the feeler arm 14 being subsequently rocked, further unwinding of the weft thread is prevented, so that during the next following traverse of the shuttle the thread is broken

and the central detector for feeling the weft thread is caused to stop the loom. Due to the fact that with this arrangement the feeler member is only released for operating incidental to the shuttle beginning its traverse overstretched picks are positively avoided.

With a view to avoiding the spare winding, the weft feeler member may be provided with a rounded point instead of with the portion 17. With this arrangement, the rounded point enters 80 between the weft windings proper, shortly before the complete exhaustion of the weft, at a moment, where the resistance offered by the remaining windings has become small enough to permit this.

I do not limit myself to the particular size, shape, number or arrangement of parts as shown and described, all of which may be varied without going beyond the scope of my invention as shown, described and claimed.

What I claim is:

1. In a loom shuttle for use in weaving looms provided with a weft detector member arranged for the immediate stopping of the loom before the next throw of the slay, in combination with a spool spindle, a slotted tubular carrier for the weft thread, mounted on said spool spindle, a movable, inertia-actuated weft feeler member arranged in the spool spindle and which contacts from within against the weft thread and projects through the slot of the carrier and thereby prevents further 100 unwinding of the weft thread, so that the weft thread detector enters into action by the breaking of the thread on the following throw.

2. In a loom shuttle for use in weaving looms provided with weft detectors for stopping the loom 110 before the next throw of the slay, in combination, a loom shuttle body, a spool supporting spindle pivoted to said body, a slotted tubular carrier for the weft windings surrounding said spindle, a weft feeler member operatively connected with 115 said spindle and adapted to cooperate with said weft windings on said carrier through the slot in said carrier, operating means provided for said feeler member, for automatically projecting the feeler portion of said member into operative 120 position through said slot in said carrier in response to the impacts imparted to the shuttle in the longitudinal direction of the same, for feeling the weft thread and blocking the same on substantial depletion of the weft, stop means for 125 locking and releasing said operating means for said feeler member in accordance with the direction of the slay moving forwards or rearwards and incidental to the end movement of the shuttle and the starting movement of the same on its traverses, the blocked weft thread of the loom shuttle being torn by action of the traversing movement of the shuttle so that the weft thread detector enters into action by the breaking of the thread 130 on the following throw.

3. In a loom shuttle for use in weaving looms provided with weft detectors for stopping the loom before the next throw of the slay, in combination, a loom shuttle body, a spool supporting spindle provided with a transverse bore, a slotted 140 tubular carrier for the weft windings surrounding said spindle, a weft feeler member operatively connected with said spindle and adapted to cooperate with said weft windings on said carrier through the slot in said carrier, operating means provided for said feeler member, for automatically projecting the feeler portion of said member into operative position through said slot in said carrier in response to the impacts imparted to the shuttle in the longitudinal direction of the same, 145

for feeling the weft thread and blocking the same on substantial depletion of the weft, a stop ball adapted to cooperate with said feeler member and guided in said transverse bore of said spindle for 5 free movement in the axial direction of said bore, for locking and releasing said operating means for said feeler member, in accordance with the direction of movement of the slay moving forwards or rearwards and incidental to the end

movement of the shuttle and the starting movement of the same on its traverses, the blocked weft thread of the loom shuttle being torn by action of the traversing movement of the shuttle so that the weft thread detector enters into action 80 by the breaking of the thread on the following throw.
